(57) **CLAIM**

The ornamental design for a light head, as shown and described.

DESCRIPTION

FIG. 1 is a front perspective view of a light head in accordance with a first embodiment of the present invention;

FIG. 2 is a rear perspective view of the light head illustrated in FIG. 1;

FIG. 3 is a top plan view of the light head illustrated in FIG. 1;

FIG. 4 is a rear plan view of the light head illustrated in FIG. 1;

FIG. 5 is a front plan view of the light head illustrated in FIG. 1;

FIG. 6 is a side plan view of the light head illustrated in FIG. 1;

FIG. 7 is a front perspective view of a light head in accordance with a second embodiment of the present invention;

FIG. 8 is a rear perspective view of the light head illustrated in FIG. 7;

FIG. 9 is a top plan view of the light head illustrated in FIG. 7;

FIG. 10 is a rear plan view of the light head illustrated in FIG. 7;

FIG. 11 is a front plan view of the light head illustrated in FIG. 7; and,

FIG. 12 is a side plan view of the light head illustrated in FIG. 7.

The features of the light head shown in dotted line are for illustrative purposes only and form no part of the claimed design.
